UNITED STATES PATENT OFFICE

109,310

DESIGN FOR A REFLECTOR LENS OR THE LIKE

Clark M. Bolser, Cedar Falls, Iowa, assignor to
The Bolser Corporation, Cedar Falls, Iowa, a
corporation of Iowa

Application August 23, 1937, Serial No. 71,291

Term of patent 7 years

To all whom it may concern:

Be it known that I, Clark M. Bolser, a citizen
of the United States and a resident of Cedar
Falls, in the county of Blackhawk and State of
Iowa, have invented a new, original, and orna-
mental Design for a Reflector Lens or the like,
of which the following is a specification, reference
being had to the accompanying drawing, forming
part thereof.

Figure 1 is a front elevational view of a reflector
lens or the like showing my new design;

Figure 2 is an edge elevational view thereof;
Figure 3 is a rear elevational view thereof; and
Figure 4 is a sectional view on the line 4—4 of
Figure 3.

I claim:

The ornamental design for a reflector lens or
the like substantially as shown.

CLARK M. BOLSER.
